CLAIM

The ornamental design for a screw type base for relays, as shown and described.

DESCRIPTION

FIG. 1 shows a front perspective of a screw type base for relays;

FIG. 2 shows a front elevation thereof;

FIG. 3 shows a rear elevation thereof;

FIG. 4 shows a right side thereof;

FIG. 5 shows a left side thereof;

FIG. 6 shows a top side thereof;

FIG. 7 shows a bottom side thereof; and,

FIG. 8 shows a rear perspective thereof.

The broken lines in the drawings depict portions of the screw type base for relays that form no part of the claimed design.

1 Claim, 8 Drawing Sheets
